UNITED STATES PATENT OFFICE

2,625,918

FLUID HEATING APPARATUS

Thomas M. Lumly, Tulsa, Okla.

Application January 19, 1949, Serial No. 71,692

13 Claims. (Cl. 122—356)

1

This invention relates to new and useful improvements in heaters and the primary object of the present invention is to provide an apparatus for heating fluids such as oil, water and the like.

Another important object of the present invention is to provide a heating unit that is divided into two heating zones and having banks of tubes in said heating zones, and embodying novel and improved means for controlling and proportioning the heat absorbed by the tubes.

Yet another object of the present invention is to provide an upshot heater having a pair of convection tube banks mounted therein and a heat resisting, preferably chrome-nickel alloy steel, curtain or partition interposed between the pair of banks for regulating the amount of heat absorbed by each of the banks of convection tubes.

Another feature of the present invention is to provide a fluid heater divided into two heating zones by a preferably chrome-nickel partition adjacent which there is supported a pair of banks of radiant tubes, said partition reflecting radiant heat to greater external surfaces of the radiant tubes than was heretofore possible with the commonly known gravity-type center wall heaters.

Another feature of the present invention is to provide a fluid heater including a steel curtain dividing the heater into two sections or heating zones, said curtain being vertically adjustable for controlling the amount of combustion gases entering the upper portion of the heater and more particularly the convection tube partition of the heater.

A further object of the present invention is to provide a fluid heater including a novel and improved damper construction controlling the passage of the products of combustion from the heater into the stack.

A still further aim is to provide a fluid heater that is simple and practical in construction, strong and reliable in use, small and compact in structure, highly efficient and durable in operation, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the heater constructed in accordance with the present invention;

2

Figure 2 is a transverse vertical sectional view taken substantially on the plane of broken section line 2—2 of Figure 3;

Figure 3 is a fragmentary longitudinal vertical sectional view taken substantially on the plane of section line 3—3 of Figure 2;

Figure 4 is a fragmentary group perspective view showing the manner in which the steel curtain is secured to the curtain supporting beam;

10 Figure 5 is a fragmentary group perspective view showing the damper construction of the present heater; and,

Figure 6 is a fragmentary group perspective view showing the tube supports and framework used in conjunction with the present invention.

Referring now to the drawings in detail, wherein for the purpose of illustration, there is disclosed a preferred embodiment of the present invention, the numeral 10 represents the heater generally, including a plurality of longitudinally spaced inverted, substantially U-shaped frame members 12 the lower ends of which are anchored to a foundation 14. The upper ends of a pair of I-beams 16 are secured to the web of each frame member 12 and the lower ends 17 of the beams 16 incline outwardly and downwardly and are secured to the legs of the frame members 12 intermediate the ends thereof. The inner flanges of the beams 16 support a plurality of vertically spaced pairs of ears 18 that receive tongues 20 projecting from the ends of a plurality of tube supporting I-beams 22, it being understood that the tongues 20 are removably secured to the ears 18 by any suitable means so that the supporting beams 22 may be quickly and readily removed for cleaning purposes in a convenient manner.

40 The lower of the supporting beams, which are referred to by the numeral 24, are secured by fasteners or the like 26 to the upper flanges of further I-beams 28 having downwardly and inwardly sloping end portions 30.

45 The beams 22 are spaced from each other and from the beam 24, and the webs of all of the beams 22, 24 and 28 are provided with groups of openings or apertures 32 that receive first and second banks or groups of longitudinally extending convection tubes 34 and 36. The groups of tubes 34 and 36 are reversely bent back and forth and include laterally projecting end portions 38 and 40 forming inlets for fluids that are to be directed through the said convection tubes.

50 From the lower flanges of the I-beams 28 there depend elongated vertical support beams or webs 55 42 having laterally projecting, vertically spaced,

tube holding hooks or arms 44 on both sides thereof. The arms 44 are formed with concaved recesses that receive banks of reversely bent radiant tubes 46 and 48 which are integrally formed with the convection tubes 34 and 36.

The tubes 50 and 52 carried by the supporting beams 28 are termed compensation tubes since these tubes compensate for the relatively high temperature differential which usually exists between the radiant and convection tube banks.

Suitably fixed to the inner flanges of leg portions of the frame members 12, below the portions 17, is a plurality of longitudinally extending fire resistant refractory walls 54 forming the side walls of the instant heater. Refractory inner walls 56 are fixed to the inner faces of the side walls for a purpose which will later be more fully apparent.

Further refractory side walls 58 are secured to the inner flanges of the beams 16 and the upper portions of the side walls 58 are joined by an upper wall 60 having downwardly sloping end portions 62.

The space between the side walls 54 and 58 are closed by sloping walls 64 thereby completing the sides of the heater as well as the upper wall.

The heater 10 is provided at each end with end walls 66 in order to complete the enclosure for the combustion chamber and a selected one, or both, of the end walls 66 are provided with suitable openings and closures, such as 68 and 70, for the openings.

The banks of tubes 46 and 48 are provided with longitudinal extensions or outlets 72 and 74 that extend outwardly through one of the end walls 66.

Secured to the upper wall 60 at the center thereof, is a base plate 76 having an opening in which there is fixed, by welding or the like, a sleeve 78. A pair of semi-cylindrical fire walls 80 are fixed within the sleeve 78 and diametrically opposed anchor strips 82 are mounted between adjacent edges of the walls 80 and project into the interior of sleeve 78.

The sleeve 78 receives a baffle plate 84 the edges of which are secured to the strips 82 by fasteners or the like. The baffle plate 84 is disposed longitudinally of the heater 10 and includes upper longitudinal projections 86 that rest upon the upper edge of the sleeve 78.

An extension plate 88 is rigidly secured to and depends from the baffle plate 84 and this extension plate is received in an annular opening 90 in the upper wall 60 for a purpose later to be explained.

Embracing the sleeve 78, is a damper structure designated generally by the numeral 92 that includes a cylindrical member or stack having inner and outer walls 94 and 96 between which there is mounted a fire wall or sleeve 98.

The outer wall 96 supports a ring member 100 that is braced to the outer wall 96 by a plurality of circumferentially spaced channel members 102.

Diametrically opposed supports 104 are mounted on the ring member 100 and each support a pair of bearings 106 and 108 that rotatably receive the outwardly projecting ends of a pair of spaced shafts or rods 110 and 112 that are journaled on the cylindrical member, or walls 94, 96 and 98, for rotation. The rods 110 and 112 are disposed longitudinally of the heater 10 and are fixed to the diametrical edges of semi-circular damper plates or valves 114 and 116.

The rods 110 and 112 are rotated by any suit-

able means so that the plates 114 and 116 may be maintained at a predetermined raised position, and independent actuating means are associated with each rod whereby the rods are individually rotated to control the products of combustion passing from each of the heating zones 118 and 120 in the heater 10.

A pair of longitudinally extending I-beams 122 and 124 are fixed to the upper wall 60 and include downwardly inclined outer ends 126 that are secured to the ends 62 of the upper wall. The inner ends of the beams 122 and 124 are bent about opposite sides of the sleeve 78 and support the lower edges of the walls 94, 96 and 98.

The webs of the frame members 12 are joined by longitudinal connecting beams 128 and the beams 128 are braced by spaced cross beams 130 that support the ring member 100, together with the central portions of the beams 128.

Fixed to the uppermost of the supporting beams 22, is a longitudinally extending plate or plates 132 having supporting and reinforcing webs 134. The longitudinal side edges of the plate 132 about the inner faces of walls 58 and the end edges of the plate 132 are spaced from the end walls 66 to permit a passage for the combustion products to pass about the ends of plate 132 toward the opening 90.

Disposed longitudinally of the heater 10 and between the banks of tubes 36, 52, 48 and 34, 50, 46, is a plurality of vertically extending steel curtains or partitions 138, of preferably nickel-chrome alloy, which are spaced sufficiently to accommodate the supporting beams 22, 24 and 28.

The upper edges of the curtains 138 are shaped to conform to the upper wall 60 and the portions 62 of the upper wall, and the curtains are provided with a plurality of openings 140 that receive U-bolts 142. The legs of the bolts 142 extend through the upper wall 60, including portions 62, and the lower flanges of the beams 122 and 124, including portions 126, and the threaded ends of U-bolts receive holding nuts that are adjustable for retaining the curtains in a vertically adjusted position.

Suitable hanger bolts or the like 144 hold the central curtains or partitions 146 to the extension plate 88.

The heater 10 is provided with a refractory floor 148 beneath which there is mounted a row of burners 150 that are disposed on both sides of the curtains. The burners communicate with the heating zones 118 and 120 by firing ports 152 provided in the floor. Flames and hot combustion gases issuing from the burners are directed in a substantially continuous sheet against opposite sides of the side walls formed by members 54 and travel upwardly to heat the same to a highly radiant condition. Heat is transmitted from the flames and hot combustion gases and from the hot refractory faces of the side walls 54 to the curtains or partitions and hence to the surfaces of the radiant tubes 46 and 48 disposed adjacent the curtains. The resulting combustion gases from which substantial quantities of radiant heat have been extracted pass from the heating and combustion zones 118 and 120 into zones 154 and 156 wherein the tubes 34 and 36 are heated.

It should be noted, that by extending the curtains 138 and 146 between both pairs of radiant tubes, convection tubes and compensation tubes, a more desirable and efficient heating of the tubes is accomplished than was heretofore possible. Also, the partitions or walls 138, 146 and plates 114 and 116 will permit individual regulation of

the combustion products from the heating zones 120, 158 and 118, 156, therefore, different types of liquids or fluids may be directed through the banks of the tubes 36, 52, 48 and 34, 50, 46 and maintained at a predetermined temperature without the necessity of altering the symmetry between pairs of tube banks as shown in the drawings.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A heater comprising an enclosure having an upper wall, said upper wall having an opening therein, a partition depending from and attached solely to said upper wall, banks of tubes held stationary within the enclosure adjacent both sides of and free from said partition, said enclosure being divided into two zones by said partition, damper means controlling the flow of products of combustion through said opening, and means adjustably securing the partition to the upper wall for vertical adjustment of the partition within the enclosure and relative to the banks of tubes.

2. The combination of claim 1 wherein said damper means includes a sleeve rising from said opening, a partition mounted in said sleeve and dividing the same into a pair of passages communicating with the respective zones, and a damper plate controlling each of the passages, said partition in said sleeve overlying the partition dividing the enclosure into two zones and said partitions being coplanar.

3. The combination of claim 1 and a common support for the walls of said enclosure and said tubes, said common support including a plurality of substantially U-shaped frame members and cross beams terminally secured to said frame members and supporting said banks of tubes.

4. A heater comprising an elongated enclosure having an upper wall and an opening in said upper wall, a plurality of metallic curtains disposed in said enclosure and attached solely to said upper wall, hanger means removably and adjustably securing the curtains to the upper wall, said curtains dividing said enclosure into a pair of heating zones, adjacent curtains being spaced from each other, a plurality of vertically displaced transverse beams mounted in said enclosure and located in the space between adjacent curtains, first and second banks of convection tubes carried by said beams and spaced from each other by said curtains, a support depending from said beams, first and second groups of radiation tubes mounted on said support and disposed on opposite sides of said curtains and spaced from said curtains, and damper means controlling the flow of products of combustion from the heating zones by way of the opening in said upper wall, said damper means including a stack concentric with said opening and having a partition member therein overlying said curtains.

5. The combination of claim 4 wherein the

enclosure includes a reduced upper portion in which said banks of convection tubes are mounted, said groups of radiation tubes being mounted in the central portion of said enclosure and beneath said banks of convection tubes.

6. In a fluid heater including an enclosure having an upper wall, an upper convection tube partitioned zone and a lower radiation tube partitioned zone; means for controlling the amount of combustion gases entering the convection partitioned zone comprising, a chrome-nickel alloy steel curtain disposed vertically within the enclosure and terminating above the bottom of the enclosure, said curtain dividing the enclosure into the aforementioned zones and hanger means adjustably securing the curtain to the upper wall for adjustment of the curtain vertically within the enclosure, said curtain being attached solely to said upper wall.

7. In a fluid heater including an enclosure having an upper wall and a reduced upper portion, a pair of banks of convection tubes mounted in said upper portion, and a metallic curtain hanging from said upper wall and terminating above the bottom of the enclosure, said curtain extending between said pair of banks for controlling the amount of heat absorbed by each of the banks of convection tubes, said curtains being free from said banks to permit removal of the curtain independently of the banks.

8. The combination of claim 7 wherein said curtain extends downwardly into the lower portion of said enclosure, and a pair of banks of radiation tubes mounted in the lower portion of said enclosure and separated by said curtain.

9. In a fluid heater including an enclosure having an upper wall, a partition depending from and adjustably secured to said upper wall and dividing the enclosure into first and second heating and combustion zones, banks of tubes mounted in each of said zones, said upper wall having an outlet opening therein, and a damper construction controlling the flow of products of combustion from said zones through the outlet opening, said damper construction including an upstanding partitioned stack having a vertical plate therein, and a pair of swingable damper plates disposed in said stack, said partition being parallel to said banks of tubes and coplanar with said plate.

10. The combination of claim 9 and a burner disposed beneath the partition and adapted to direct its flame along sides of the enclosure, and refractory surfaces mounted in said enclosure and spaced parallel to said partition to receive the flame of said burner.

11. A heater comprising an enclosure including an upper wall having an opening therein, first and second banks of longitudinally extending tubes mounted in said enclosure, a partition disposed longitudinally of and between said banks of tubes, and adjustable hanger means securing the partition to the upper wall for adjustment of the partition vertically with respect to the banks of tubes, said partition being attached solely to said upper wall and free from said tubes.

12. A heater comprising an enclosure including a reduced upper portion having an upper wall, first and second upper bands of longitudinally extending reversely bent tubes in said upper portion, support members mounted solely within said upper portion supporting said first and second upper bands of tubes, additional support members hanging from said first named members and entering the enclosure from its reduced upper

75

portion, first and second lower banks of tubes attached solely to said additional support members, and a vertically disposed metallic curtain hanging from said upper wall and extending between the first and second upper banks of tube and also extending between the first and second lower banks of tubes, said curtain being free from said banks of tubes and terminating above the bottom of the enclosure.

13. In an up-shot type heater including an enclosure including a reduced upper portion having an upper wall, a plurality of spaced parallel vertical supports mounted within the upper portion and including lower reduced portions extending downwardly from the upper portion and into the enclosure, first and second upper banks of tubes supported by said members within the upper portion of the enclosure, first and second lower banks of tubes attached to said lower reduced portions of said supports, and a thin vertically disposed curtain attached solely to and supported by the upper wall and extending downwardly between the first and

second upper banks of tubes and also extending downwardly between the first and second lower banks of tubes, said curtain being removably secured to said upper wall and free from said supports and said banks of tubes to permit removal of said curtain.
